UNITED STATES PATENT OFFICE.

ULYSSES S. BROWN AND LUCY E. BROWN, OF LOGANSPORT, INDIANA.

WASHBOARD.

1,240,118.

Specification of Letters Patent. Patented Sept. 11, 1917.

Application filed December 1, 1916. Serial No. 134,425.

To all whom it may concern:

Be it known that we, ULYSSES S. BROWN and LUCY E. BROWN, citizens of the United States, residing at Logansport, in the county 5 of Cass and State of Indiana, have invented new and useful Improvements in Washboards, of which the following is a specification.

This invention relates to improvements 10 in wash boards, one object of the invention being to provide a wash board, with a hood at the upper end thereof which projects forwardly therefrom and which serves to prevent suds from splashing over the wash 15 board and also presents a concave upper surface which fits the head of the board to the body of the user.

Another object of the invention is to provide means for securing the wash board to 20 the side of the tub and holding the board in position for use.

Another object is to provide an improved soap holder for the wash board which serves to feed the soap forwardly as it is used 25 and obviates the necessity of handling the soap and also effects an economy in the use of the soap.

With the above and other objects in view the invention consists in the construction, 30 combination and arrangement of devices hereinafter described and claimed.

In the accompanying drawings:

Figure 1 is a front elevation of a wash board constructed and arranged in accordance with this invention.

Fig. 2 is a detailed vertical sectional view of the same on the plane indicated by the line 3—3 of Fig. 1.

Fig. 3 is a detailed transverse sectional view of the same on the plane indicated by the line 4—4 of Fig. 1.

The side bars of the wash board are shown at 1 and the rubbing surface at 2. In accordance with the invention a hood 3 is provided for the wash board which is 45 preferably made of sheet metal but may be made of any suitable material. The hood is provided with sides 4 which are secured on the outer sides of the bars 1 of the wash 50 board and are substantially triangular in shape and widened forwardly and upwardly and project from the front side of the wash board, at the upper end thereof, as shown. The hood also has a top portion 55 5 which extends across the top or head of the board and which is downwardly cen-

trally curved so that the hood presents a concave upper surface which adapts the upper end of the board to fit against the person of the user and renders the use of 60 the board more comfortable. The upper portion of the hood also projects forwardly from the wash board so that the hood effectively prevents suds from splashing over the top of the board.

To secure the board to one side of the tub and hold the board firmly in place when in use in the tub we provide a pair of catches 6 each of which is pivotally mounted as at 7 on the outer side of one of the side 70 bars 1 of the board. The catches have downwardly extending arms 8 to engage on the outer side of the wall of the tub and are also provided each with a curved slot 9 concentric with the pivot.

Clamping screws 10 work in said slots and are engaged in threaded openings in the bars 1 and serve to secure the catches at any desired adjustment. The lower ends of the bars 1 are beveled as at 11 and are 80 also beveled on their rear sides as at 12 to enable the wash board to be snugly fitted in the bottom of the tub.

The wash board is provided at a point above the rubbing surface with an opening 85 13 to permit a bar of soap to project forwardly through the same. A soap receiving compartment 15 is arranged on the rear side of the wash board, is open at its outer side and is provided with a hinged cover 90 16. Reinforcing spring bars 17 extend transversely across the rear side of the wash board, one of said spring bars passing across the rear side of the soap receiving compartment.

A soap holder 18 is provided which comprises a pair of members 19 to bear against the rear side of a bar or cake of soap, said members having inturned points 21 at their outer ends to engage in the ends of the soap. Said members also have rearwardly inturned flanges 22 in their inner ends and are connected together by coiled retractile springs 23 which serve to draw said members toward each other and cause them 100 to clamp and hold the bar of soap securely between them. An arched spring 24 has its arms slidably connected to the soap holding members and has its central portion connected to a plate 25 which bears 105 against the rear wall of the soap holding compartment and is detachably held be-

tween said rear wall and flanges 26 on the inner sides of the end walls of said compartment, as shown in Fig. 4. The said arched spring serves to force the soap forwardly so that the front side of the soap is projected forwardly a sufficient distance from the surface of the board to cause the articles which are being washed to be rubbed against the front side of the soap. 10 and to be soaped thereby. The soap holder may be removed from the compartment by first raising the cover 16, as will be understood, to permit the removal or the renewal of the bar of soap as may be desired. 15 While we have herein shown and described a preferred form of our invention we would have it understood that changes may be made in the form, proportion and construction of the several parts without departing from the spirit of our invention and within the scope of the appended claims. 20

Having thus described our invention, what we claim is:

25 1. A wash board having an opening, a

structure in the rear of said opening forming a soap receiving compartment, a soap holder detachably arranged in said compartment and comprising a pair of soap clamping members, springs to draw said soap clamping members toward each other and a spring slidably connected to said members and also serving to force the same and the soap forwardly.

2. A wash board having an opening, a structure in the rear of said opening forming a soap receiving compartment and having an opening in the upper side and also having a closed rear side and flanges in its end walls spaced slightly from the rear side, a soap holder and a plate to which the soap holder is attached, said plate being removable from the compartment through the upper side of the latter and when in the compartment being held between the rear wall and said flanges of the compartment.

In testimony whereof we affix our signatures.

ULYSSES S. BROWN.
LUCY E. BROWN.
